UNITED STATES PATENT OFFICE

JUSTUS C. ZUBLI, OF BREMERTON, WASHINGTON

STENCILING OR IMPARTING MACHINE

Application filed July 28, 1927. Serial No. 208,900.

My invention relates to machines for stenciling or otherwise imparting to an object or surface a design, and it is particularly concerned with machine for carrying out the 5 method described in my application, Serial No. 52,301, although, by this machine, a design may be imparted to a surface without the use of stencils or diverters.

One object of my invention is to provide 10 a machine which is sufficiently flexible to give, through mechanical means, the various shadings of tone and color which might be obtained through hand work, and which can mechanically reproduce over and over the 15 same designs or effects, whether by the use of stencils, or by traversing an air gun over a predetermined path without using stencils.

In large measure, then, my invention has 20 relation to the production of a stenciling or imparting machine which is capable of a wide variety of adjustments, and which may go through various cycles.

Another object is the production of a machine capable of traversing a sheet from side 25 to side and lengthwise, simultaneously, to cover the entire surface thereof, and, more specifically, such a machine wherein the spray guns are carried on a slide movable longitudinally of a carriage which is itself 30 movable transversely, and the control of these two movements from a common drive and timing device.

Among the objects having to do with the mechanism embodied in my machine, it is an 35 object to provide means for controlling the discharge of stenciling media, automatically or otherwise, whereby as a spray gun approaches a surface, its discharge may be diminished or cut off.

Again, it is an object to include in such a 40 machine a timing control whereby the machine may be set to complete a given cycle or cycles, and then be stopped.

Other objects, especially such as pertain to 45 mechanical arrangements, will appear hereinafter.

My invention comprises the novel parts 50 and the novel combination and arrangement thereof, as shown in the accompanying drawings, described in the specification, and par-

ticularly defined by the claims terminating the same.

In the accompanying drawings, I have shown my invention in the form which is now preferred by me. 55

Figure 1 is a general plan view of the machine.

Figure 2 is a section on line 2—2 of Figure 1, looking toward the top of the sheet in that figure. 60

Figure 3 is a section along the line, looking in the opposite direction.

Figure 4 is a view similar to a portion of Figure 3, showing a slightly modified form.

Figure 5 is a view substantially on the 65 line 5—5 of Figure 1.

Figure 6 is a view substantially on the line 6—6 of Figure 5.

Figure 7 is a side elevation of one of the spray guns, and Figure 8 is a side elevation 70 thereof, taken from a point of view at right angles to Figure 7.

My invention contemplates the provision of means for creating motion of one or a series of spray guns or like elements, typifying a source of projection of a stenciling or imparting means, in various directions in a horizontal plane, and further, the movement of these spray guns or like elements to cause them to approach and recede from a surface, 75 and to permit their discharging at various selected angles. It contemplates also the mechanical reproduction of any desired cycle, so that a plurality of surfaces or objects may be stenciled cheaply and as copies 80 one of another, so that any given design may be reproduced, as many times as may be desired, by this process. The invention contemplates various types of control for such movements, and both the means for obtaining 85 these movements and their control may vary widely in mechanical form. However, I will proceed to describe the machine in its present embodiment.

The surface to be stenciled is indicated at 90 S, supported upon a table T. This table may be stationary, but preferably is supported upon a ball and socket joint J, so that long shadow effects may be obtained by tilting it, or the angle of the stencils relative to the 100

direction of the spray discharge may be varied. Instead of moving the spray guns G, it may be found preferable to control movement of the table. However, as shown herein, 5 two spray guns or air brushes, representing any number that it may be desired to employ, are positioned above the table and directed toward it, so that a surface and diverters or stencils supported thereon will be affected by 10 the material discharged from the guns G. These spray guns are mounted upon a carriage 1, which, in turn, has a slide 10 guided at 11 in the support 1. The carriage 1, in turn, is guided in the base B, or other fixed member.

15 By means of a reciprocable arm 13, the carriage 1 may be moved transversely as seen in Figure 1, to move the guns G over the table T, and through the medium of an arm 14, carrying a transversely slotted head 15, this transverse movement of the carriage 1 may be permitted and at the same time, the slide 10 may be given a longitudinal movement relative to the carriage 1 and relative to the table T. By 20 these or like means, any combination of movements in a horizontal plane can be given to the spray guns G.

25 Various operating means may be provided for the arms 13 and 14, though, preferably, 30 each goes through a common control to the motor M, which is a common source of power. Thus, the motor M drives a pinion 90 engaging a gear 91, by means of which a drive shaft 9 is rotated continuously. From this 35 shaft power is delivered to a crank arm 21 by means of meshed gears 92 and 93, this crank arm operating a pitman 22 adjustably connected through the set bolts 23 with a lever 24 pivoted about the shaft 2, and carrying a 40 ratchet gear 25 engaging a ratchet wheel mounted on the shaft 2. Also secured on the shaft 2 is a cam or eccentric 3, which has engaged therewith a follower 30 by means of which an arm 31, guided at 32, may be reciprocated.

45 It will be noted in Figure 1 that the arm 31 is parallel with the arm 14, guided at 17 on the base B. The connection between these arms 14 and 31, as herein shown, comprises a 50 walking-beam arrangement, as a lever 33, pivoted at 34 on the frame and having adjustable pivot bolts 35 and 36 at its ends, connecting, respectively, with the arms 31 and 14. The pivot of the arm is slidable in a slot 37 55 and the support 38 is likewise slotted, as indicated at 39 in Figure 2, whereby the pivot 34 may be adjusted towards either of the pivots 35 or 36, or the entire lever may be shifted one way or the other, to adjust the leverage 60 of the two arms. In this manner adjustment of the throw of the arm 16 may be obtained and, consequently, a change in the amount of movement of the slide 10 may be obtained. This movement, it will be remembered, 65 controls longitudinal movement of the guns G.

To control movement of the main carriage 1, like means may be employed, or, as shown herein, the shaft 9 is provided with a cam 95, with which is engaged a cam follower 5 upon the end of a sliding rod 50 guided upon the base at 51. This sliding rod 50 is parallel with the arm 13, and movement is transmitted from the rod 50 to the arm 13 in the same manner as between the rods 31 and 14, hence the description for the one will suffice for the other, it being understood in this instance that the connection at 36' corresponds to the connection at 36, and the connection at 35' corresponds to the connection at 35.

70 By means of the constructions just described, it is possible for the carriage 1 to be given movement, the amount of which is controlled by the location of the pivot 34 of its controlling arm 33, and for the slide 10 to be given movement which is similarly controlled 75 and which may vary with respect to the carriage, so that longitudinal movement predominates, or the reverse. This movement occurs in regular cycles, owing to the common drive through the shaft 9 of these members. 80 The timing of the various elements may also be controlled through the use of different cams at 3 and at 95.

85 It is highly desirable that some means be provided for continuing the movement of such devices through one, two, three or more cycles, whichever is deemed preferable. Thus, the device may be so arranged that the cam 3 is given one revolution through the ratchet drive described, for four revolutions 90 of the cam 95, and it may be desirable to permit the cam 3 to go through one revolution, only, or two, or perhaps three, to cover the surface intended. To this end I have provided on the shaft 2 a gear meshing with the gear 20, with which is associated electric contacts which are included in the circuit to the motor M (see Figures 1 and 2). A contact 27, adjustably mounted on the base, contacts with a drum 28, secured to rotate with the 95 gear 20. Both the contact 27 and the drum 28 are electrically connected in the motor circuit. The drum has insulating insets 29 arranged at different levels, one level having one only, the next level two insets, etc. By 100 positioning the contact 27 at any selected level the motor can be stopped once, twice, three times, or any selected number of times for one revolution of the drum 28. As the latter is synchronized with the main drive 105 shaft 9, being positively driven therefrom, this forms a convenient way of synchronizing the entire cycle of operations, and of stopping the operation at a proper point in the cycle, to remove a completed surface and permit the positioning of another on the table T. This should always be at a time when the guns have cleared the table, to permit a 110 setting of stencils or diverters to be picked up intact, so that they will be maintained in 115

their proper relationship to the entire design, all as has been referred to in my application referred to above.

As has been noted it is sometimes desirable 5 to move the guns G toward the surface S, or to cause them to recede therefrom. To accomplish this object, when desired, I have provided a worm pinion 40 on the main drive shaft 9, meshing with a worm gear 41 on a 10 vertical shaft 42, this shaft carrying also a friction disc 4 with which is engaged a slideable friction disc 43 mounted upon a shaft 44, the shaft 44 being journaled at 45 upon the base B and being connected by universal 15 joints 46, and the telescoping shaft 47, to a shaft 48 on the slide 10 which carries a gear 49.

The gear 49 meshes with a gear 50 upon a shaft 51 journaled at 52 upon the slide 10. 20 On this shaft 51 are secured eccentrics or like members 5 to control the several guns G. This may be accomplished through rocker arms 53 pivoted at 54 from a bracket 55 supported on the slide 10, or in any other suitable manner. One end of the rocker arm is 25 connected to the eccentric strap or rod 56, and its other end is connected to a sleeve 60 controlling movement of the spray gun. Parallel movement is achieved through a link 57 also secured to the bracket 55 and to the sleeve 60, so that the sleeve 60 always maintains its vertical position.

In the sleeves 60 are carried the main supports for the guns G. Preferably these take 35 the form of rods 6 slidable and rotatable within the sleeves G, and normally clamped in place therein, as by the set screws 61 (see Figure 3). The lower ends 62 of the rods 6 are bent laterally, and on these laterally bent 40 ends are clamped the brackets 70 in which the guns G are directly clamped, as by means of the set screws 71. The rods 6 can be turned within the sleeves 61, or adjusted at any height therein, thus varying the initial setting 45 of the guns G with respect to the surface S.

The friction drive 43, 4, introduces an element of possible variation, which may be desirable in order to change each card stenciled, and to give it a slightly individual touch. However, where exactness of reproduction is desired, it can be made certain by 50 substituting gears 4' and 43' for the friction discs 4 and 43, respectively (see Figure 4).

It will be understood that the guns G may 55 be of any construction desired, and, ordinarily, would be of much the same construction as any ordinary spray gun if the stenciling medium is a liquid coloring, or mordant, or like liquid stenciling medium. However, I prefer that they be controlled 60 electrically, and to that end I provide a projecting rod 7 forming part of or connected to the usual control valve in the nozzle of 65 the spray gun. A spring 72 interposed be-

tween a collar 73 on the stem 7 and an ear 74 formed on a bracket 75 tends to move the rod 7 in the direction which will normally close the control valve. A further extension of the stem 7 carries a grooved piston valve 76, 70 in the air line to the nozzle. The position of this piston valve 76 along the stem 7 is controlled by a turn buckle 77, or like adjusting means. Movement of the valve extension 7 is controlled by a lever 78, pivoted at 79 and engageable by one end with a collar 7' adjustable along the rod 7.

It will be apparent that as the nozzle approaches the surface being stenciled, it will deliver a concentrated spray. To avoid too great concentration, an electromagnet 8 may be used to cut off the spray at such times. This attracts the arm 78, connected to the valve stem 7, when energized, its limit of movement being determined by the adjustable stop 80. To energize the magnet a contact 81 is carried by the gun or by its supporting rod 6, and this contact may be vertically adjustable thereon. A complementary contact 82 is fixed to the slide 10, or the bracket 55 mounted thereon. As the gun, carrying the contact 81, moves downward, this contact eventually comes into contact with the contact 82, completing the circuit through the electromagnet 8. This moves the valve 95 stem 7 in a direction to close the valve. It should be noted that such movement of the valve stem closes the air conduit by means of the valve 76, and stops all discharge of air or stenciling medium from the nozzle. 100

It is believed that the operation of the device will be clear; it will also be clear how various adjustments can be effected, creating an endless variety of the most beautiful shaded and colored effects, as described in my application referred to above. 105

The characteristics of reproductions are affected by several factors, and especially when consecutive copies are to be uniform these factors must be maintained uniformly 110 throughout the operation of making the reproductions. Aside from many differing characteristics of surfaces for imparting or stenciling media, there are also to be considered time of exposure, force of air pressure 115 with which media is discharged, angle of discharge, and path of impact upon the surface. As each of these factors will affect the reproduction materially, it is evident that automatic means, such as have been described, are 120 required to maintain the effect caused by any individual factor, and to cause the consecutive copies to be uniformly alike.

While it forms no part of the present invention, and has been described in my application referred to above, it will be necessary, if the diverters or stencils are to be maintained in their proper relative location, to use electromagnetism, or some like force, to anchor them upon the surface S. Especially 125 130

is this true when the surface is of a smooth nature, like glass, for instance. Also, to handle the diverters, that is, to lift them to permit removal of a completed sheet and insertion of a new sheet, electromagnetic means, or some other such means as are described in my previous application, must be employed.

What I claim as my invention is:

1. A machine of the character described, comprising a table, a projector, and means for moving said table and projector relative to each other, and controlling such movement to cause said projector to traverse the table through a predetermined path, and means for adjusting the drive means to determine any selected path.

2. A machine of the character described, comprising a table, a projector, means for causing relative movement of said table and projector to traverse the projector over the table, and automatic means operating during such movement to lessen or increase the distance of said projector from the table.

3. A machine of the character described, comprising a table, a projector, means for causing relative movement of said table and projector to traverse the projector over the table, means operable during such movement to lessen and increase the distance of said projector from the table recurrently, and means for varying the relative timing of the traversing and of the projector's movement.

4. A machine of the character described, comprising a table, a projector, means for reciprocating said projector longitudinally of said table, other means operable at the same time for reciprocating said projector transversely thereof, and means adjustable to vary the amount of each movement.

5. A machine of the character described, comprising a table, a projector, means for causing relative movement therebetween longitudinally of the table, other means for causing relative movement therebetween transversely of the table, and common drive means for simultaneously operating said two first-mentioned means.

6. A machine of the character described, comprising a table, a projector, means for causing relative movement therebetween longitudinally of the table, other means for causing relative movement therebetween transversely of the table, and a common drive means for said two first-mentioned means, including means for varying the relative timing of the transverse and longitudinal movements.

7. In a machine of the character described, an air gun, a table, means for traversing said gun both longitudinally and transversely relative to said table, means for advancing said gun towards and withdrawing it from said table, means controlling discharge from said gun, and means initiating action of and controlling said discharge-controlling means

in accordance with its elevation above the table.

8. In a machine of the character defined, a table, a spray gun, means for moving said spray gun in a predetermined path over said table, while said gun delivers an uninterrupted spray, said drive means for the spray gun including means for regulating the time of exposure of a surface upon said table to the discharge from said spray gun.

9. In a machine of the character described, an air gun, means for approaching the nozzle of said gun in the direction of a surface being stenciled, discharge control means movable with said gun, and means cooperating with said control means, and positioned to be contacted thereby at a desired limit of such approach to interrupt the discharge from said gun.

10. In a machine of the character described, an air gun, means for approaching the nozzle of said gun in the direction of a surface being stenciled, discharge control means movable with said gun, and means cooperating with said control means, and positioned to be contacted thereby at a desired limit of such approach to interrupt the discharge from said gun, and means for adjusting the relative positions of said two latter means to vary the point in the approach of said gun where said latter means becomes operative.

11. In a machine of the character described, a table, an air gun, a support therefor, means for adjusting the angle of said air gun relative to and its distance from said table, means for traversing said air gun over said table through a predetermined path, and means for automatically stopping said mechanism at the end of a selected cycle.

12. In a machine of the character described, an air gun, a slide supporting said air gun, a carriage in which said slide is longitudinally slidabile, and means for simultaneously sliding said slide longitudinally of the carriage, and for moving the carriage transversely.

13. In a machine of the character described, an air gun, a slide supporting said air gun, a carriage in which said slide is longitudinally slidabile, means for simultaneously sliding said slide longitudinally of the carriage, and for moving the carriage transversely, means for reciprocating said gun vertically relative to the slide, and driving and timing means distant from the carriage for controlling movements of said carriage, said slide, and said gun.

14. In a machine of the character described, an air gun, a slide supporting said air gun, a carriage in which said slide is longitudinally slidabile, an arm projecting from each of said slide and carriage, a lever connecting with the end of each arm, drive means movable through an unchanging dis-

tance for rocking said levers, and means for adjusting the leverage in each lever to vary the throw of either or both.

15. In a machine of the character described, an air gun, a slide supporting said air gun, a carriage in which said slide is longitudinally slideable, a common drive, and means interposed between said drive and said carriage and slide, to simultaneously move each, and an automatic stop device operable from said common drive.

16. In a machine of the character described, an air gun, a slide supporting said air gun, a carriage in which said slide is longitudinally slideable, means for simultaneously sliding said slide longitudinally of the carriage, and for moving the carriage transversely, a shaft journaled on said carriage, an eccentric on said shaft, operative means connecting said eccentric with the air gun to reciprocate the latter, and a drive for said shaft connecting and synchronized with said carriage and slide moving means.

17. A machine of the character described, comprising a table, a projector, means for moving said table and projector relative to each other, and controlling such movement to cause said projector to traverse the table through a predetermined path, and means for varying the plane of said table relative to the plane of movement of said projector.

18. A machine of the character described, comprising a table, a projector, means for moving said table and projector relative to each other, and controlling such movement to cause said projector to traverse the table through a predetermined path, and means for rotating the table about an axis included in the path of said projector.

19. In a machine of the character described, an air gun, a rod having a vertical shank and a horizontal arm, means for clamping said air gun upon the horizontal arm at any desired angle, a sleeve receiving said vertical shank, means for retaining said shank in said sleeve at any height and in any rotated position about its axis, and means for reciprocating said sleeve through a fixed path.

50 Signed at Bremerton, Kitsap County, Washington, this 22d day of July, 1927.
JUSTUS C. ZUBLI.
